UNITED STATES PATENT OFFICE.

ROBERT JARVIS SMOthers, OF HOLYOKE, MASSACHUSETTS, ASSIGNOR TO JAMES T. ROBINSON, OF HOLYOKE, MASSACHUSETTS.

PRINTING ROLL.

Application filed September 11, 1925. Serial No. 55,805.

This invention relates to a textile printing roll and the invention has for its object to provide, in a manner as hereinafter set forth, a printing roll for printing on fabrics, and including a roll body having removably secured thereto a printing plate in cylindrical form and with the opposed edges of the plate in abutting, overlapping, engagement to provide a substantially seam-
5 less impression surface, whereby the free edges of a design to be printed can be matched to form an impression surface having a continuous design for application to the fabric.

15 As is well known in textile printing, the design to be applied to the fabric is an inherent part of the printing roll, and to produce the same the roll, which is generally in the form of a hollow copper body, al-
20 though in some instances it is in the form of a solid copper cylindrical body, having the periphery thereof engraved, or otherwise treated, partially thereof or completely throughout to provide the design which is
25 to be printed on the fabric. After the printing operation, the roll is generally discarded, but in some instances smoothed off or reduced in diameter to enable the engraving or treating the periphery thereof to pro-
30 vide a new design for printing, and which entails considerable time, expense, labor and loss. A textile printing roll in accordance with this invention is an improvement upon the form of plate roll as set forth in my
35 applications S. Nos. 728,425 and 12,409 filed respectively July 26, 1924 and May 22, 1925, and not only possessing the objects and ad-
40 vantages as set forth in the applications aforesaid, but has for its further object to overcome the welding or soldering of the plate to the roll body, as the connection now employed between the plate and roll body is a detachable one formed by removably mounting of plate attaching bars within the
45 sections of the roll body to connect the plate, with overlapping edges, in the form of a true cylinder on the roll body, and by such arrangement there is provided a printing roll having the printing plate removably secured to the roll body, and after the plate has been used, it is removed from the roll body and the latter again employed for other plates, and which overcomes the expensive,
50 tedious, and slow engraving step, as well as

the discarding or smoothing of the roll 55 body. Under such conditions, a material saving in operating cost is obtained.

With the foregoing and other objects in view, the invention consists of the novel form of textile printing roll as will be hereinafter more specifically described and illustrated in the accompanying drawings, but it is to be understood that changes, varia-
60 tions and modifications can be resorted to which come within the scope of the claims 65 hereunto appended.

In the drawings wherein like reference characters denote corresponding parts throughout the several views:—

Figure 1 is an elevation, partly in section, 70 of a printing roll in accordance with this invention.

Figure 2 is a section on line 2—2 Figure 1.

Figure 3 is a view of the plate looking 75 towards one edge thereof when extended.

Figure 4 is a fragmentary view, in section, taken on line 4—4 Figure 2.

Figure 5 is an end view showing the sec-
80 tions of the body portion of the roll extend-
ed and having the plate connected therewith.

Referring to the drawings in detail, the plate is indicated at 1 and consists of a body portion of bendable sheet metal of a desired thickness and which has its outer face 2 pro-
85 vided in any suitable manner with a design, not shown, which is to be printed upon the material operated on. The design is so dis-
posed on the plate that when the latter is 90 bent in the form of a true cylinder and se-
cured to the plate roll the free edges of the design will be matched to form a continuous design which is to be printed on the material or transferred to be printed on the material 95 during the operation of offset printing. The horizontal edges of the plate 1 are bevelled, as at 3, 4, so that when the plate is in the position shown in Figure 5, the said edges not only abut, but will overlap to provide 100 for the matching of the free edges of a de-
sign whereby a continuous design is set up. The bevelled edge 3 extends at an inward in-
clination whereas the bevelled edge 4 extends at an outward inclination, or in other words, 105 the bevels are disposed in parallel inclined planes to provide for the positioning of the edges in the manner as heretofore set forth, when the plate is mounted on the plate roll.

Secured to each end of the plate, at the inner face thereof, and flush with the bevelled edges 3, 4 is a pair of attaching bars 5, 6 which extend from one side edge to the other side edge of the plate 1. The bar 5 is of less width than the bar 6, but both bars are of the same height and length. That face of the bar 5 which is secured to the inner face of the plate 1 is of greater width than that face of the bar 6 which is secured to the inner face of the plate 1. The inner face of the bar 7 is inclined or bevelled throughout upon the same plane and the outer face of the bar 5 is formed upon vertical and inclined planes, intercepting each other. The bevelled and straight portions on the outer face of the bar 5 are indicated at 8, 9 and the bevelled edge forms a continuation of the bevelled edge 3. The bar 6 has its inner face bevelled or inclined, as at 10, which extends in the same plane throughout and the outer face of the bar 6 has the outer portion thereof bevelled or extending upon an inclined plane as at 11 and which forms a continuation of the bevelled edge 4. The inner portion of the outer face of the bar 6 is straight as at 12 and when the plate is connected to the roll body said inner part 12 is positioned in a plane parallel to the plane of a horizontal diameter of the roll. The inner portion of the bar 5 is of greater width than the outer portion thereof and the inner portion of the bar 6 is also of greater width than the outer portion thereof. The outer portion of the bar 5 is in the form of a parallelogram and the inner portion substantially in the form of a triangle. The outer and inner portions of the bar 6 are of triangular contour.

The supporting roll, to which the plate 1 is attached, comprises a body portion formed of two semi-cylindrical sections and means coacting with the ends of said sections for maintaining them in abutting engagement. One of the sections of the roll body is generally referred to by the reference character 13 and the other by the reference character 14. As both sections of the roll body are of like construction, but one will be described, as the description of one will apply to the other. Each roll body section is formed with a reduced extension at each end and each extension is formed of an inner portion 15 having a tapered periphery 16. Each of said extensions further include a reduced semi-cylindrical portion 17 provided with peripheral threads 18. A semi-cylindrical portion 17 merges in the outer end of the tapered portion 16. When the extensions of the section 13 are arranged in coacting relation with respect to the extensions of the section 14, the tapered portion 15 of an extension of the section 13 forms a continuation of the tapered portion 15 of the section 14 and this statement also applies to the re-

duced portion 17 of the section 13 with respect to the reduced portion 17 of the section 14.

The inner face of the section 13 is formed with a series of spaced sockets 19, and in which are adapted to extend, when the roll sections are in abutting engagement, holding pins 20 which are secured to and project from the inner face of the section 14. The pins 20 when engaged in the sockets 19 prevent the sections 13 and 14 from shifting relatively to each other.

The inner face of the section 13 is cut away to provide a triangular shaped pocket 21 which opens at the periphery of said section, and the section 14, at its inner face is cut away to provide a triangular shaped pocket 22 which opens at the periphery of the section 14. The pockets extend from one end to the other end of said roll sections and are of the same depth, but the pocket 22 is of greater width than the pocket 21 throughout. The pocket 21 is adapted to receive the attaching bar 5 and the pocket 22 the attaching bar 6. The width of the inner end of the attaching bar 5 is less than the width of the pocket 21 at its inner end. When the attaching bar 5 is mounted in the pocket 21 the inclined face 7 thereof abuts against the inclined wall 23 of the pocket 21. The attaching bar 5 when mounted in the pocket 21 does not extend completely over the bottom of the pocket 21. The attaching bar 6 is of a width greater than the width of the pocket 22 and in said pocket is mounted said bar 6. When the roll sections are held in abutting engagement, the attaching bar 6, enters pocket 21 and seats on the bottom thereof, as well as abuts against the outer face of the bar 5, see Figure 5. The attaching bars 5 and 6 coact with the pockets 21 and 22, to couple or secure the plate 1 to the roll body in the manner as shown in Figure 5. By shifting the roll sections 13 and 14 to a position so that the inner faces thereof will extend at an inclination with respect to each other, the attaching bars 5 and 6 can be removed from the pockets 21 and 22 whereby the plate 1 can be shifted from off the roll body.

As before stated, means are arranged at each end of the sections of the roll body, for the purpose of maintaining them in abutting engagement, whereby the plate 1 when connected with the roll body by the attaching bars and pockets, will be secured thereto, so that the plate can be used for printing purposes. The means at each end of the sections of the roll body prevent the separation thereof, when in abutting position, and under such conditions prevent any outward movement of the plate 1 with respect to the roll body. The means which is arranged at each end of the roll body, coacts with the threaded portions 17 and the

tapered portion 15 for securely maintaining the sections 13 and 14 in abutting position, as illustrated in Figure 3. The securing means at one end of the roll body 5 is the same as the other end, and only one of the said means will be described, as the description of one will apply to the other.

Each of the said securing means consists of a spindle 24, of substantial length, and which at its inner end is formed integral with a cylindrical head 25 of materially greater diameter than the spindle 24. Formed integral with the head 25, is an annular cap piece 26 having a portion of its inner face bevelled as at 27 and the remaining portion threaded as at 28. The flaring portion 27 is plane and wedges against the plane tapered peripheral face of a pair of abutting portions 15 and the threads 28 on the inner face of a cap 26 engage with the threads 18 on a pair of abutting portions 17, see Figure 3. The securing means, at each end of the roll body, may be termed coupling members and not only connect or secure 20 the sections 13, 14 together, due to the threaded engagement of the coupling members with the part 17. The bevelled portion 27 of the cap acting upon the tapered portions 15 set up a wedging or binding action 25 so that the sections 13 and 14 will be held abutting against each other throughout.

After the plate 1 has been used, it is removed from the sections 13, 14, and the roll body can then be employed for other plates. The connecting of the plate to the roll body in the manner as stated, sets up the plate in the form of a true cylinder and with the opposed edges of the plate in abutting, overlapping engagement, to provide 30 for the matching of the free edges of a design whereby a continuous design is set up when printing.

As the plate is constructed independently 45 of the roll, after the plate has been used, it does not necessitate the discarding or smoothing of a roll for when the plate is removed from the roll another plate can be immediately attached thereto.

It is thought that the many advantages 50 of a printing roll, in accordance with this invention, for use in printing textile and wall paper can be readily understood from the foregoing description taken in connection with the accompanying drawing, and although the preferred embodiment of the invention is as illustrated and described, yet it is to be understood that changes in the details of construction can be had which will fall within the scope of the invention 55 as claimed.

What I claim is:—

1. A printing roll comprising a body portion formed of a pair of sections adapted 60 to be detachably secured together in abutting engagement and each having the inner

face thereof provided with a lengthwise extending pocket, a bendable metallic printing plate having opposed edges thereof bevelled to overlap when the plate is bent in cylindrical form, a pair of attaching bars secured to the inner face of said plate and each having a bevelled face forming a continuation of a bevelled edge of the plate, said bars seated in said pockets to connect the plate in enveloping position with respect to and against the periphery of said body portion, and means engaging with the ends of said sections when in abutting engagement for detachably securing said sections together thereby maintaining the edges of 70 said plate in overlapping or abutting position.

2. A printing roll comprising a body portion formed of a pair of sections adapted to be detachably secured together in abutting engagement and each having the inner face thereof provided with a lengthwise extending pocket, a bendable metallic printing plate having opposed edges thereof bevelled to overlap when the plate is bent in cylindrical form, a pair of attaching bars secured to the inner face of said plate and each having a bevelled face forming a continuation of a bevelled edge of the plate, said bars seated in said pockets to connect the plate in enveloping position with respect to and against the periphery of said body portion, and means engaging with the ends of said sections when in abutting engagement for detachably securing said sections together thereby maintaining the edges of 80 said plate in overlapping or abutting position.

3. A printing roll comprising a body portion formed of a pair of sections adapted

to be detachably secured together in abutting engagement and each having the inner face thereof provided with a lengthwise extending pocket, a bendable metallic printing plate having opposed edges thereof bevelled to overlap when the plate is bent in cylindrical form, a pair of attaching bars secured to the inner face of said plate and each having a bevelled face forming a continuation of a bevelled edge of the plate, said bars seated in said pockets to connect the plate in enveloping position with respect to and against the periphery of said body portion, and means engaging with the ends of said sections when in abutting engagement for detachably securing said sections together thereby maintaining the edges of said plate in overlapping or abutting position, and each of the pockets are of the same length as the length of a bar and of triangular contour.

4. A plate roll comprising a body portion formed of a pair of semi-cylindrical sections

- adapted to be detachably secured together in abutting engagement and each having the flat face thereof provided throughout with a lengthwise extending triangular pocket, 5 a bendable metallic printing plate having opposed edges thereof bevelled to overlap when the plate is bent in cylindrical form, a pair of attaching bars secured to the inner face of said plate and each having a bevelled 10 face forming a continuation of a bevelled edge of the plate, said bars seated in said pockets to connect the plate in enveloping position with respect to and against the periphery of said body portion, each of said 15 pockets opening at the inner face and at the periphery of a section, one of said pockets being of greater width than the other, and one of said bars being of greater width than the other. 20 5. A printing roll comprising a body portion formed with a pair of detachably connected abutting sections provided on their inner faces with pockets extending lengthwise thereof and opening at the periphery 25 of said sections and further opening at the inner faces of the sections, said pockets being of triangular contour and one of greater width than the other, a bendable metallic printing plate provided on its inner face with attaching bars mounted in said pockets for connecting the plate in enveloping position with respect to and against the periphery of said body portion, and means for 30 detachably connecting said sections in abutting engagement. 35 6. A printing roll comprising a body portion formed with a pair of detachably connected abutting sections each provided on its inner face with a pocket opening at the periphery of its respective section, a bendable metallic printing plate provided on its inner face with a pair of attaching bars each flush with one edge of a plate, said bars seated in said pockets for connecting the plate in enveloping position with respect 40 to and against the periphery of said body portion and with the opposed edges of the plate abutting, and means for detachably connecting said sections in abutting engagement. 45 7. A printing roll comprising a body portion formed with a pair of detachably connected abutting sections each provided on its inner face with a pocket opening at the periphery of its respective section, a bendable metallic printing plate provided on its inner face with a pair of attaching bars each flush with one edge of a plate, said bars seated in said pockets for connecting the plate in enveloping position with respect 50 to and against the periphery of said body portion and with the opposed edges of the plate abutting, and means for detachably connecting said sections in abutting engagement. 55 8. A printing roll comprising a body portion formed with a pair of detachably connected abutting sections each provided on their inner faces with interengaging means to prevent the shifting of the sections relatively to each other when the sections are 60 in opposed relation. 65 9. A printing roll comprising a body portion formed with a pair of detachably connected abutting sections each provided on their inner faces with interengaging means to prevent the shifting of the sections relatively to each other when the sections are 70 in opposed relation. 75 ROBERT JARVIS SMOTHERS.
